UNITED STATES PATENT OFFICE.

GEORGE HENRY WHEARY, OF RACINE, WISCONSIN.

REMOVABLE TRUNK-PAD.

1,381,952.

Specification of Letters Patent. Patented June 21, 1921.

Application filed June 10, 1919. Serial No. 303,099.

To all whom it may concern:

Be it known that I, GEORGE HENRY WHEARY, a citizen of the United States, and resident of Racine, in the county of Racine 5 and State of Wisconsin, have invented new and useful Improvements in Removable Trunk-Pads, of which the following is a description, reference being had to the accompanying drawings, which are a part of 10 this specification.

This invention relates to improvements in removable trunk pads.

This invention relates to removable trunk pads more particularly adapted for retaining garments in suspended position on garment hangers in the wardrobe section of a 15 wardrobe trunk.

In wardrobe trunks of the better type as now constructed the trunk body is divided 20 vertically medially into two sections which are hinged together and are adapted to swing horizontally to open or closed position. One of these sections is usually provided with drawers and other compartments 25 and the other section, called the wardrobe section, is usually provided with garment hanger tracks upon which garment hangers are slidably mounted. The tracks are usually of the extensible type to permit the 30 hangers to be slid outwardly on the track while in suspended positions. Garments are suspended on and folded over the hangers and in order to permit them to be freely removed from the trunk section the 35 upper end of the section is open and is provided with a cover which may be swung upwardly to open position. In trunks of this type it is necessary to provide means for engaging the hangers and garments to 40 securely hold them in position and prevent their accidental disarrangement during transportation and without injury to the garments.

It is one of the objects of the present invention to provide the wardrobe section of a wardrobe trunk with a removable means for firmly and yieldingly holding the hangers and garments carried thereby in position within the said section.

50 A further object of the invention is to provide a removable trunk pad which may be easily attached to or removed from the upper end portion of the wardrobe section of a trunk.

55 A further object of the invention is to provide a removable trunk pad which is of

very simple construction, is strong and durable and is well adapted for the purpose described.

With the above and other objects in view 60 the invention consists of the improved removable trunk pad and its parts and combinations as set forth in the claims, and all equivalents thereof.

In the accompanying drawings in which 65 the same reference characters indicate the same parts in all of the views:

Fig. 1 is a top view of a portion of a wardrobe trunk shown in open position and provided with the improved removable pad; 70

Fig. 2 is a vertical sectional view thereof, on a larger scale, taken on line 2—2 of Fig. 1;

Fig. 3 is an enlarged sectional detail view taken on line 3—3 of Fig. 1; and 75

Fig. 4 is a sectional detail view taken at right angles to Fig. 3.

Referring to the drawing, the numeral 5 indicates the trunk body generally which is divided vertically to form a drawer section 6 and a wardrobe section 7 hinged thereto and arranged to be swung horizontally to open or closed position. The upper end of the wardrobe section is open and is provided with a cover 8 which, while shown as hinged 80 to the drawer section, may if desired be hinged to the wardrobe section, but in either construction will close the open end of the wardrobe section. The cover is provided with front and side depending flanges 9 and 10 which are connected to the top by angular corner edge reinforcing members 11. These reinforcing members 11 form inside angular edge recesses 12 which are utilized to connect the pad 13 to the top. 95

Garment hanger tracks 14 mounted in the upper portion of the wardrobe section have garment hangers 15 slidably and removably mounted thereon which are adapted to support and have garments folded over the upper horizontal edges 15' thereof. Said horizontal edges are parallel to and positioned a short distance from the top cover. 100

The removable pad is formed of soft yielding material and is interposed between 105 the upper edges 15' of the hangers and the top cover and is of greater thickness than the space between said edges and the cover so that the upper hanger edges and the apparel draped thereover will embed in the 110 pad in the manner shown in Fig. 4 and be maintained in adjusted position on the

tracks. In order to prevent the pad from injuriously abrading or rubbing apparel of delicate material, due to vibration of the parts during transportation, the pad is filled 5 with a soft yielding but firm material and the covering 13' of the pad is preferably of very soft silky material like plush. When the pad is thus formed the most delicate wearing apparel may be held on the hangers 10 without injury and without requiring pressing when the trunk has reached its destination and is unpacked.

In order to removably hold the pad connected to the top cover the pad is mounted 15 on a board or flat non-flexible material 16 and said board is reinforced along its opposite side edges by metal reinforcing strips 17 of angular form in cross section. The front ends 18 of these strips project forwardly from the front edge of the pad board and extend into one of the angular edge recesses 12 of the trunk. The said ends 18 are curved to form offset or shouldered portions 18' which lock the end portions to 25 the trunk cover when positioned in the edge recesses. The inner ends 19 of the strips are formed with semi-circular edge recessed portions 19' which are engaged by angular locking buttons 20. These buttons are pivoted 30 on the inner face of the cover and may be swung into engagement with the strips to lock the pad in position.

The angular portions of the buttons also engage the circular recesses 19' and prevent 35 longitudinal movement of the pad.

In use the pad is removably mounted in the trunk cover in the manner shown and wearing apparel is draped in the usual manner over the garment hangers and the top 40 cover is closed. The upper edges of the hangers and the portions of the garments draped thereover will be yieldingly embedded in the pad and maintained in adjusted position without injury and in a manner to eliminate repressing.

From the foregoing description it will be seen that the removable trunk pad is of very simple construction and is well adapted for the purpose described.

50 What I claim as my invention is:

1. The combination with a trunk having a wardrobe section with a top cover and garment hangers slidably mounted in the ward-

robe section adjacent the cover, the top cover being shaped to form an inside angular recess, of a pad therefor comprising a non-flexible pad member interposed between the top cover and the garment hangers and having a pad member formed of soft yielding material on its lower face and into which the upper edge portions of the hangers or apparel draped thereon embed when the top cover is in closed position, said pad having a covering of soft non-abrading material, reinforcing members mounted on the opposite side portions of the non-flexible pad member and projecting outwardly therefrom in offset relation thereto and extending into the inside angular recess, and buttons pivoted to the top cover and lockingly engaging 70 portions of the opposite end of the reinforcing member.

2. The combination with a trunk having a wardrobe section with a top cover and garment hangers slidably mounted in the wardrobe section adjacent the cover, the top cover being shaped to form an inside angular recess, of a pad therefor comprising a non-flexible pad member interposed between the top cover and the garment hangers and having a pad member formed of soft yielding material on its lower face and into which the upper edge portions of the hangers or apparel draped thereon embed when the top cover is in closed position, said pad having 80 a covering of soft non-abrading material, reinforcing members mounted on the opposite side portions of the non-flexible pad member and projecting outwardly therefrom in offset relation thereto and extending into the inside angular recess, the opposite end portions of the reinforcing members being recessed, and angular buttons pivoted to the top cover and lockingly engaging the recessed portions of the reinforcing members. 90

3. A removable trunk pad, comprising a non-flexible member having a pad portion formed on one of its side faces with a covering of soft non-abrading material, and reinforcing members mounted on the opposite side edge portions of the non-flexible member and having front and side edge projecting offset portions for easily removable connection with a trunk cover.

In testimony whereof, I affix my signature. 105
GEORGE HENRY WHEARY.
